(57) CLAIM

The ornamental design for a sports memorabilia holder, as shown and described.

DESCRIPTION

FIG. 1 is a perspective view of a sports memorabilia holder showing my new design, the broken-line disclosure of a baseball being for illustrative purposes only and forming no part of the claimed design;

FIG. 2 is an additional perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is bottom plan view thereof.
